CLOCK

Ralph L. Tweedale, Dayton, Ohio

Application August 13, 1930, Serial No. 475,049

8 Claims. (Cl. 58—35)

This invention relates to electric clocks and has for its purpose the provision of a novel means and method of setting such clocks.

It is an object of this invention to provide in 5 an electric clock, means for setting the hands controlled from a distance over the usual wires feeding the clock.

It is also an object of the invention to provide 10 an electric clock having means for setting the hands to any of a plurality of positions.

It is a further object to provide a method of 15 setting electric clocks from a distance.

Another object is to provide a hand-setter 20 which is driven from the same source of power 15 which normally drives the hands.

Another object is to provide an electric clock 25 which is capable of being set to any hour indication.

A further object is to provide a novel master 30 clock for controlling electric clocks.

It is also an object to provide a novel escapement mechanism which may be driven from a 35 usual rotary motor and which imparts energy to a time keeping element such as a pendulum with 25 a frictionless drive between the escapement and the time keeping element.

It is an object also to provide a clock escapement having a freely swinging time keeping element which may swing without having any frictional drag imposed upon it by the escapement. 40

It is a further object to provide a clock setting system in which a synchronous motor clock is set to various time indications by a master clock, located at a distance, over the usual line wires 45 feeding the clock.

Another object is to provide a synchronous motor clock having means for striking the hours which are controlled from the master clock located at a distance.

40 A further object is to provide a clock and clock system of the type mentioned above which shall be relatively simple and shall avoid complex mechanism, especially at the secondary clock.

Other and sundry objects will appear from a 45 study of the following description, the drawings, and the claims.

The preferred embodiment of the invention is illustrated in the accompanying drawings in which,

50 Fig. 1 is a diagrammatic or exploded view in perspective of a synchronous motor clock embodying my invention.

Fig. 2 is a detail view of a part of the resetting mechanism, being a partial section on line 2—2 55 of Fig. 1.

Fig. 3 is a wiring diagram of one embodiment of the invention.

Fig. 4 is a rear view of a master clock driving mechanism embodying the novel escapement mechanism, and

Fig. 5 is a wiring diagram of a modification of the clock setting system.

Synchronous motor clocks are gradually finding a wider use and sale on account of their greater accuracy when properly set, and on account of the comparatively low price at which an accurate clock can be manufactured and sold. 10 A big disadvantage of the synchronous motor clocks now in use, however, lies in the fact that whenever there is an interruption in the current 15 supply the clock stops. This results in great inconvenience because the clock must be set after every current interruption. This objection is keeping many people from using the electric clocks now on the market and it is an object of 20 this invention to overcome this difficulty and provide an electric clock which can be relied on to keep accurate time even though the current supply is often interrupted, temporarily.

Briefly the embodiment of the invention illustrated contemplates setting the minute hand of a synchronous motor clock by a conventional heart-cam mechanism which is operated by a power take-off from the clock train at a relatively fast moving point in the train. For setting 30 the hour hand there is provided a notched disc connected to the hour hand and having a single notch. A pawl is driven clockwise a predetermined distance, depending on the hour, to pick up the notch in the disc and if it is behind time 35 bring the notch up to the correct position corresponding to that particular hour. The pawl is driven by the same power take-off which drives the minute hand setter. The operation of the power take-off is controlled by an impulse sent 40 out from a master clock and super-imposed on the normal alternating current transmitted to the synchronous motor clock. The master clock may be located either at the power station with the master clock which regulates the frequency 45 of the alternating of the alternating current, or at a local point of distribution such as an apartment, school, office building, etc., in which are located several synchronous motor clocks, or it may be the same master clock which regulates 50 the frequency of the alternating current, or it may be located at any point desirable.

The escapement mechanism of the master clock comprises a pair of impulse springs which have their effective pivot points coincident with that 55

of the pendulum. One of the impulse springs is tensioned by a lever which is held in position by the friction of the spring acting in a substantially radial direction to the pivot point of the lever. This lever when thus held in spring tensioning position locks the escapement wheel. As the pendulum moves toward the spring it moves it back far enough to release the lever which swings out from under the spring which is then free to impulse the pendulum. The lever, having unlocked the escapement wheel, allows the wheel to turn far enough to move the opposite lever to spring tensioning position. The opposite lever also locks the escapement wheel when it has come to this position. The same cycle of operations is repeated by each lever and spring alternately.

In Fig. 1 a self-starting synchronous motor 2 is driven from a suitable source of regulated alternating current, and includes the shading coils 4 and rotor 6. The rotor 6 drives a pinion 8 by means of shaft 10. Pinion 8 drives a gear 12 which drives shaft 14 carrying rigidly mounted thereon a gear 16. The broken away gears 18 represent any suitable reduction gear train which is well known in the art and is shown diagrammatically for sake of clearness. Gear train 18 reduces the rapid motion of pinion 20, fastened to gear 12, to a relatively slow motion (one revolution per hour) of gear 22. Gear 22 is yieldably mounted on shaft 24 by means of a friction connection 26. Shaft 24 carries a heart-cam 28, a pinion 30, and at its outer end the minute hand 32, all rigidly mounted. Hour hand 34 is rigidly fixed upon sleeve 36 which is freely rotatable on shaft 24. Sleeve 36 carries rigidly at its rear end a disc 38 having a notch 40. Yieldably mounted on sleeve 36 by means of a friction connection 42 is a gear 44. The gear 44 is driven at a reduced rate (one revolution in twelve hours) from pinion 30 by means of the gears 46 and 48 mounted on shaft 50. Freely rotatable on shaft 24 next to disc 38 is a gear 52, carrying a pawl 54 adapted to engage notch 40. The gear 52 is yieldably held in any position by the friction brake 56.

Pivoted to the frame 58 at 60 is a lever 62 carrying a roller 64 adapted to cooperate with the heart-cam 28 when lever 62 is raised. Lever 62 is raised by a cam 66 on shaft 68 and cooperating with a roller 70 on lever 62. The cam 66 is formed with a spiral rise portion in the first 180° of rotation from the position shown and in the direction of the arrow in Fig. 1. The remaining 180° of cam 66 is a dwell portion which acts to retain the lever 62 in raised position and thus through the medium of cam 28 and roller 64 hold the minute hand 32 stationary during setting of the hour hand 34 as will be seen later.

Also mounted on shaft 68 is a mutilated gear 72 having teeth on only 180° of its periphery. The mutilated portion of gear 72 is arranged so that it passes the teeth of gear 52 during the same portion of counter-clockwise rotation of shaft 68 as that during which the rise portion of cam 66 raises lever 62. As the dwell portion of cam 66, turning counter-clockwise, comes under roller 70 the first teeth of gear 72 engage the teeth of gear 52 to turn it in a clockwise direction. Gear 72 carries a pin 74 on which is carried the inner end of a spiral spring 76 the outer end of which is mounted on a pin 78 fastened to the frame. The spring 76 is wound by counter-clockwise rotation of shaft 68 and its associated parts and is adapted to return them to a normal position determined by stop pins 80, 82 when shaft 68 is released as explained here-

after. Rigidly mounted at the forward end of shaft 68 is a drive gear 84. The drive gear 84 is driven from the power take-off gear 16 through a shiftable pinion 86. The pinion 86 is carried on a shaft 88 mounted on a lever 90. Lever 90 is carried by a sleeve 92 loosely rotatable on shaft 14 and is yieldably held against a fixed stop 94 by an adjustable spring 96. The lever 90 may be moved to engage pinion 86 with gear 84 by means of an armature 98 mounted on sleeve 92. The armature 98 may be attracted by an increased flux in the field structure of motor 2 as shown in Fig. 1 or it may be attracted by a separate electro-magnet 100 as shown in Fig. 5.

Referring to Fig. 2 it will be seen that the right hand edge of notch 40 is inclined from the radial so that the point of pawl 54 overlays the vertex of notch 40 when gear 52 comes to the position shown in Fig. 2 by a counter-clockwise movement. But when the gear 52 comes to the same position by a clockwise movement the pawl 54 will fall into notch 40.

Referring now to Fig. 4 there is shown the master clock driving mechanism comprising a weight motor 102 which is preferably of the self winding type. It is to be understood that the showing is merely diagrammatic and the motor may be of any type exerting a substantially constant torque reliably. The motor 102 turns shaft 104 which through the gear train 106, 108, 110 turns pinion 112 in a counter-clockwise direction. Pinion 112 is rigidly connected to escapement wheel 114. This wheel comprises a disc 114 on which is the raised portion 116 having the locking projections 118 and the raised cocking portions 120. Pivoted mounted on the frame at 122, 124 are a pair of levers 126, 128 carrying rollers 130, 132 adapted to engage the raised portions of the escapement wheel 114. Levers 126, 128 also carry rollers 134, 136 adapted to engage alternately a pair of impulse springs 138, 140 which are fastened to the clamp 142. The clamp 142 is carried on the frame and also mounts the spring 144 which supports the pendulum 146 carrying the impulse arms 148, 150. The ends of springs 138, 140 are so shaped that when either roller 134 or 136 is raised the corresponding spring is tensioned and the lever is locked in raised position as lever 128 in Fig. 4. In this position the wheel 114 is locked by roller 132 abutting against the radial side of a locking projection 118. Stop pins 152, 154 are mounted on the frame to limit the inward movement of springs 138, 140.

Referring to Fig. 3, 156 represents the snail cam of a conventional striking mechanism which is mounted in the usual way on the master clock. The rack 158 is analogous to the rack of a conventional striking mechanism the only difference between it and a conventional rack being that rack 158 has twenty-four working teeth instead of the usual twelve. A gathering pin 160 is of conventional type and may be driven from a suitable motor (not shown) and which is released along with the rack 158 at every hour in a way that is well known in striking mechanisms. The rack 158 when in normal raised position as shown abuts against a bar of insulating material 162 carried by the resilient contact arm 164. Arm 164 operates contacts 166, 168 connected to arms 170, 172 respectively. Arms 164, 170, 172 are insulated from each other by the insulating mounting 174. When rack 158 is raised the contacts 166 are closed but as soon as it is re-

leased and falls contacts 168 are closed and an instant later contacts 166 are opened. The contacts remain thus until the rack 158 is again raised to normal position when the reverse operation takes place. Contact 164 is connected to a wire 176 which feeds the secondary clocks 178 which are of the type shown in Fig. 1. Contact 170 is connected to a wire 180 which leads from a source of alternating current. Contact 172 is connected by a wire 182 to a local source of direct current which is adapted to be at times super-imposed on the alternating current received. The other side of the direct current source is connected to the alternating current source by a wire 184. The other side of the alternating source is connected to the secondary clocks by a wire 186. The secondary clocks 178 are located preferably in a localized area such as an apartment, office building, school, etc. The alternating current is supplied from a distant source supplying time regulated alternating current. The master clock and the source of direct current are located in the vicinity of the group of secondary clocks 178. In this way a local group of secondary clocks can be regularly set without requiring extra mechanism at the power house which furnishes the alternating current.

The operation of the system is as follows: The weight motor 102 through the gear train 106, 112 tends to drive the escapement wheel 114 in a counter-clockwise direction. In the phase position shown in Fig. 4 the pendulum is swinging to the right after having received an impulse from spring 138. On further motion of the pendulum to the right, impulse receiving arm 150 will engage spring 140 and move it to the right a small amount. This will allow lever 128 to drop by gravity onto stop pin 180, disengaging pin 132 from the locking projection 118. This allows wheel 114 to turn under urge of the motor 102 until the opposite projection 120 has moved lever 126 clockwise far enough to lock the wheel 114 again by engagement of pin 130 with a projection 118. During this movement the left end of lever 126 moved spring 45 138 back to cocked position. Obviously as soon as lever 128 dropped, the spring 140 was free to act on the pendulum and move it to the left until spring 140 abutted against stop pin 154. On the following left swing of the pendulum the same 50 process occurs except that levers 126, 128 and associated parts take the opposite motions to those just described.

It will be noted that the only engagement of the pendulum with any escapement mechanism is the engagement between arms 148, 150 and springs 138, 140. During this engagement the arms and springs move through coinciding paths so that there is no frictional drag of one upon the other. This allows the pendulum to swing freely and 60 eliminates any frictional retarding forces which vary with the conditions of lubrication, wear, etc.

The above described escapement mechanism drives in the usual way a dial train, not shown, which controls, also in the usual way, the release 65 of the strike train motor and rack 158 and the position of snail cam 156. At a few seconds before each hour the rack 158 is released and the strike train motor is started. Contacts 168 immediately close followed by the opening of contacts 166. This disconnects wire 176 from the alternating current supply and connects it to the same through the direct current supply. While the contacts are in this position the direct current is superimposed on the alternating current thus 70 raising one component of the voltage and increas-

ing the flux in the fields of all the secondary clocks 178. This condition is maintained for a definite length of time depending on the hour at which the master clock happens to be.

When such an impulse of direct current super-imposed on alternating current is received at the secondary clock (Fig. 1) the armature 98 is attracted. This moves arm 80 counterclockwise to engage gears 84 and 86. The motor is of course running at a constant rate because the source of alternating current is regulated in the well known way so that it generates equal numbers of alternations in equal time intervals. The shaft 68 is thus connected to the motor 2 and turns in the direction of the arrow at a constant rate. During the first half revolution of shaft 68 the cam 66 raises lever 62 and by engagement of pin 64 with heart cam 28 the minute hand 32 is brought around to the hour position from any position it should happen to be in, friction connection 26 20 allowing the minute shaft 24 to be thus turned by the heart cam 28 without stalling the motor 2. After the shaft 68 has turned through one half revolution it will move through as many more twenty-fourths of a revolution as the number of 25 the hour which the master clock indicates. This is determined by the length of time armature 98 is held against field 2 which in turn depends upon the duration of the impulse received. The duration of impulse is determined by the snail cam 156 37 (Fig. 3) which controls the amount of fall of rack 158 according to the hour indicated by the master clock. For example at one o'clock the impulse will be of such duration that shaft 68 will turn through thirteen twenty-fourths of a revolution 35 and at twelve o'clock the impulse will be of such duration that the shaft 68 will turn through a full revolution (minus the necessary clearance allowances).

During whatever part of the second half revolution shaft 68 turns, gear 52 will be turned that amount by mutilated gear 72, since during the first half revolution all of the mutilated part of gear 72 passes by the gear 52. The ratio of gear 52 to gear 72 is one to two so that gear 52 is moved through as many twelfths of a revolution as the number of the hour. This enables pawl 54 to move from the twelve o'clock position (which is its normal position) to the position corresponding to the hour at the master clock. If the hour hand 34 50 should be slow it will be picked up along with disc 38 and be brought up to correct position by pawl 54. Obviously the possible correction at one o'clock is only one hour while at twelve o'clock it is twelve hours. It should be noted that the right 55 faces of notch 40 and of pawl 54 are slightly slanted so that at twelve o'clock position as shown in Fig. 2 the pawl 54 will ride on the periphery of disc 38. One clockwise revolution of pawl 54 will bring its face just up against the right side of 60 notch 40.

As soon as the impulse from the master clock ceases the armature 98 disconnects gears 84 and 86 and spring 76, which was wound during the motor driven rotation of shaft 68, will return shaft 65 68 and associated parts back to the position of rest with stops 80, 82 in engagement. When the last tooth of gear 72 leaves gear 52 the friction brake 56 holds gear 52 in normal position.

At 187 is an extension on shaft 68 which may be 70 added to the setting mechanism already described for the purpose of striking the hours. It will be seen that shaft 68 forms an ideal drive for a simple striking mechanism since it turns at each hour through an angle corresponding to that 75

hour. A disc 188 is carried rigidly by shaft 187 and has a series of twelve pins 190 arranged over 180° of its face. Pivoted at 192 is a trip lever 194. Also pivoted at 192 is another lever 196. A projection 198 on lever 194 and extending under lever 196 enables lever 194 to lift lever 196 when turned counter-clockwise but prevents movement of lever 196 when lever 194 is turned clockwise. Lever 194 is urged to a position with stop 188 against lever 196 by a spring, not shown. Lever 196 rests on a stop, not shown, in the position illustrated. When lever 196 is raised it lifts the striking hammer 200 through a connection 202. The hammer 200 when raised and dropped strikes the bar 204 which then emits the usual sound.

In operation as the shaft 68 turns, the first half revolution will bring the first pin 190 around to a position ready to operate the lever 194. As many pins 190 will pass the lever 194 thereafter as are necessary to properly strike the hour since the impulse received is of such duration that the shaft 68 turns through one half revolution plus as many twenty-fourths of a revolution as the number of the particular hour. When the impulse ceases, shaft 68 is turned back by spring 76 and the pins 190 turn lever 194 clockwise as they pass. This does not operate the lever 196, however, because it rests on the stop and the only effect is to tension the spring between levers 194 and 196.

Thus it will be seen that a simple mechanism may be added to the clock mechanism previously described which will enable the clock to strike the hours. Its simplicity flows from the fact that the means which determines how far the striking mechanism shall operate each hour is at the master clock so that only one determining means need be provided for any number of clocks. It will be understood of course that this striking mechanism may be omitted if it is not desired to have a striking clock.

In Fig. 5 is illustrated a modification which is adapted for use where the master is located at a point remote from the secondary clocks such as at the power station supplying the alternating current. It is also adapted for use in a situation where there may be one or more transformers intermediate the master and secondary clocks.

The contacts 166, 168 are controlled by the master clock in the same way as that illustrated in Fig. 3. If desired where the master clock is located at the power station the master clock may also be provided with mechanism for regulating the frequency of the alternators. Such mechanism is well known in the art.

The alternator supplying the clocks is illustrated at 206. An auxiliary alternator 208 is provided which generates a frequency different from that of the alternator 206. A transformer 210 supplies current to operate relay coils 212, 214. Relay coil 212 is connected to contacts 168 by a wire 216 and relay coil 214 is connected to contacts 166 by a wire 218. The armature 220 is arranged to be shifted back and forth by the coils 212, 214 and carries the contact bridging bar 222 which bridges the contacts 224 when coil 212 is energized. The contacts 224 are connected in a circuit 226 which connects alternator 208 in parallel with alternator 206 to feed a line circuit 228 and a transformer 230. Connected to transformer 230 are the secondary clocks 232 similar to secondary clocks 178 except for a feature mentioned hereafter. One of the secondary clocks 232 is shown in diagram and includes the motor 2 and the electro-magnet 100.

The motor 2 is connected directly to the line while the electro-magnet 100 is connected to the line through a condenser 234. The difference between clocks 232 and 178 lies in the fact that the former have separate magnets to attract armature 98 instead of using the motor field for this purpose as in Figs. 1 and 3. The capacity of condenser 234 and the inductance of magnet 100 are so chosen that they are together responsive only to the frequency of alternator 208. 10

It will be seen that at each hour the contacts 168 close and coil 212 is energized. This throws alternator 208 onto the line and the frequency of this alternator is super-imposed on the frequency of alternator 206. The magnet 100 then 15 attracts the armature 98 and the setting mechanism illustrated in Fig. 1 operates in the manner previously described.

Any other suitable means for attracting armature 98 may be utilized, the two means shown 20 being merely illustrative. It is well known that many ways are available for transmitting and receiving impulses over alternating current lines and the use of any such means is contemplated as within the scope of my invention. 25

It is to be understood that by the term "hand" is meant any time indicating or recording member such as may be driven by a clock movement, this term being used only for sake of simplicity and clearness in the claims. Likewise the term 30 "line circuit" is intended to include means for transmitting electric energy by means of radio waves.

The invention is not limited to the particular embodiments disclosed but may take any form 35 coming within the scope of the appended claims, the embodiments disclosed being for purposes of illustration only.

I claim:

1. In an electric clock having hour and minute 40 hands and motive means operated from a line circuit, the combination of means for setting the hour hand to any one of a plurality of predetermined positions, and means placed into operation by a control impulse received over the line 45 circuit for operating the setting means, the duration of the controlling impulse determining the position to which the hour hand is set.

2. In an electric clock system, a line circuit, time indicating hands, means energized from the 50 line circuit for normally driving the hands, means for periodically sending over the line circuit impulses of different durations, and means called into operation by the receipt of an impulse for setting the hands to a position which is determined by the duration of the impulse. 55

3. A clock setting system including a secondary clock having time indicating hands and a synchronous motor driving the hands at a timed rate, a line circuit feeding the motor, a master 60 clock at a distant point on the line, and means at the master clock for sending over the line impulses of different durations for setting the hands to positions determined by the duration of each impulse. 65

4. In an electric clock, an hour hand, a minute hand, timed motive means for driving the hands, means for setting the minute hand including a heart cam operatively connected with the minute hand, a driving member cooperating with the 70 heart cam to move the minute hand to a predetermined position, and means including a spring biased spiral cam and a releasable power drive connection between the motive means and the spiral cam for causing operative engagement of 75

the driving member with the heart cam, whereby the motive means of the clock moves the minute hand to a predetermined position.

5. In an electric clock, an hour hand, a minute hand, timed motive means for driving the hands, means for setting the hour hand to any of a plurality of predetermined positions, means for setting the minute hand including a heart cam operatively connected with the minute hand, a driving member cooperating with the heart cam to move the minute hand to a predetermined position, and means including a spring biased spiral cam and a releasable power drive connection between the motive means and the spiral cam for causing operative engagement of the driving member with the heart cam whereby the motive means of the clock moves the minute hand to a predetermined position, said spiral cam including a dwell portion whereby the minute hand is locked in position while the hour hand is being set.
10. In an electric clock, an hour hand, a minute hand, timed motive means for driving the hands, means for setting the hour hand including a notched disc operatively connected with the hour hand, a pawl capable of engaging the notch in the disc for moving the hour hand, a member freely rotatable about the same axis as the disc and carrying the pawl, a releasable power drive connection between the motive means and the pawl carrying member, and independently operated control means for engaging the drive connection and causing the pawl to move the hour hand to any of a plurality of predetermined positions.
15. In an electric clock, an hour hand, a minute hand, timed motive means for driving the hands, means for setting the hour hand to any of a plurality of predetermined positions, means for setting the minute hand including a heart cam operatively connected with the minute hand, a driving member cooperating with the heart cam to move the minute hand to a predetermined position, and means including a spring biased spiral cam and a releasable power drive connection between the motive means and the spiral cam for causing operative engagement of the driving member with the heart cam whereby the motive means of the clock moves the minute hand to a predetermined position, said spiral cam including a dwell portion whereby the minute hand is locked in position while the hour hand is being set.
20. In an electric clock, an hour hand, a minute hand, timed motive means for driving the hands, means for setting the hour hand including a notched disc operatively connected with the hour hand, a pawl capable of engaging the notch in the disc for moving the hour hand, a member freely rotatable about the same axis as the disc and carrying the pawl, a releasable power drive connection between the motive means and the pawl carrying member, and independently operated control means for engaging the drive connection and causing the pawl to move the hour hand to any of a plurality of predetermined positions.
25. In an electric clock, an hour hand, a minute hand, timed motive means for driving the hands, means for setting the hour hand including a notched disc operatively connected with the hour hand, a pawl capable of engaging the notch in the disc for moving the hour hand, a member freely rotatable about the same axis as the disc and carrying the pawl, a releasable power drive connection between the motive means and the pawl carrying member, and independently operated control means for engaging the drive connection and causing the pawl to move the hour hand to any of a plurality of predetermined positions.
30. In an electric clock, an hour hand, a minute hand, timed motive means for driving the hands, means for setting the hour hand including a notched disc operatively connected with the hour hand, a pawl capable of engaging the notch in the disc for moving the hour hand, a member freely rotatable about the same axis as the disc and carrying the pawl, a releasable power drive connection between the motive means and the pawl carrying member, and independently operated control means for engaging the drive connection and causing the pawl to move the hour hand to any of a plurality of predetermined positions.
35. In an electric clock, an hour hand, a minute hand, timed motive means for driving the hands, means for setting the minute hand including a heart cam operatively connected with the minute hand, a driving member cooperating with the heart cam to move the minute hand to a predetermined position, and means including a spring biased spiral cam and a releasable power drive connection between the motive means and the spiral cam for causing operative engagement of the driving member with the heart cam whereby the motive means of the clock moves the minute hand to a predetermined position, said spiral cam including a dwell portion whereby the minute hand is locked in position while the hour hand is being set.

hand, timed motive means for driving the hands, means for setting the minute hand, means for setting the hour hand including a notched disc operatively connected with the hour hand, a pawl capable of engaging the notch in the disc for moving the hour hand, a member freely rotatable about the same axis as the disc and carrying the pawl, a releasable power drive connection between the motive means and the pawl carrying member, and independently operated control means for engaging the drive connection and causing the pawl to move the hour hand to any of a plurality of predetermined positions, said drive connection including a mutilated gear whereby the setting of one hand is completed before the setting of the other hand is begun.

8. A secondary clock for use with a commercial line circuit comprising in combination time indicating hands, an electric motor energized from the line circuit, a time train for normally driving the indicating means from the motor at a timed rate, and setting means for the indicating means including mechanism responsive to an impulse of one certain character to bring at a predetermined time the indicating means to the same position from any of a plurality of positions in which the indicating means may happen to be and responsive to an impulse of another certain character to bring the indicating means to another position from any of a plurality of positions in which the indicating means may happen to be for bringing the clock to a correct time indication at a plurality of different times a day when its time indication differs from correct time by any of a plurality of amounts.

RALPH L. TWEEDALE. 35
